PROCESS OF DESULPHURIZING
PETROLEUM OILSCharles M. Ridgway, Midland, Mich., assignor to
The Pure Oil Company, Chicago, Ill., a corpora-
tion of Ohio

Application August 29, 1933, Serial No. 687,348

12 Claims. (Cl. 196—33)

- This invention relates to the treatment of petroleum oils to desulphurize the same, and comprehends a novel process and apparatus for carrying out the same; more specifically, gasoline or 5 naphtha of relatively high sulphur content is treated with an alkaline reagent, plumbite solution, followed by aging and heat treatment; together with various accessory steps; all of which are hereinafter described and claimed.
- 10 In the prior art, the conventional plumbite method of treating sour distillate is well known. Such prior operative steps include the formation of lead mercaptide and caustic soda by the reaction of sodium plumbite with the mercaptans 15 in the oil. This lead mercaptide is then treated with sulphur in the prior art to form dialkyl-disulphide together with lead sulphide, excess sulphur reacting to form various polysulphides. Various objections to this prior process embrace 20 corrosivity, actual increase of the sulphur content of the oil, and instability of the oil to the action of sunlight; the free sulphur and polysulphides being extremely corrosive and the dialkyl-disulphides having some corrosive action.
- 25 The present process obviates the disadvantages of prior methods of treatment in that sulphur is actually removed by the process through the formation of insoluble lead sulphide, while any remaining mercaptan sulphur is in the form 30 of dialkyl sulphide, which is non-corrosive and has a pleasant odor. Furthermore, formation of dialkyl sulphide increases appreciably the boiling point of the sulphur compounds and the sulphur content may be further lowered by fractionating the lower boiling treated oil from the 35 higher boiling sulphur bearing oil. The novel process and apparatus, therefore, sweetens the oil, reduces the sulphur content, and yields a non-corrosive product.
- 40 A method of carrying out the process is as follows:
- Raw untreated oil with or without carrier liquid, is scrubbed with spent caustic soda, which removes some hydrogen sulphide, free sulphur, 45 and mercaptans. A scrub with lime water is preferred at this point, although it may be omitted. The treatment then proceeds with a fresh caustic scrub followed by contact washing with sodium plumbite solution. The wash should be continued until the oil will no longer react with the 50 treating agent. The next step is to settle and age the washed oil in suitable tanks. In this settling and aging step, the oil is held above 60° F. (preferably from 70° to 80° F.) for a period approximating 100 hours, whereby the last traces of 55 moisture and sodium plumbite are removed. Some basic lead mercaptide and lead sulphide precipitate at this point. The highest temperature that can be used without excessive vapor loss is maintained in the settling and aging tanks. If 5 desired, a carrier liquid may be added during this step. After the oil has settled and aged, it is removed to a heating still. A shell still equipped with spray coils capable of jetting liquid on the bottom of the same at high velocity may be used. 10 A pipe still heater is preferably used in lieu of a shell still. Where a pipe still heater is used, sufficient pressure is maintained at the outlet of the coil to keep the oil in the liquid phase; the final temperature in the pipe still should be 15 above 250° F. and high enough to completely vaporize the oil at 5 pounds per square inch gauge pressure. In the pipe still heater, a high oil velocity and low heat input per square foot of heating surface is maintained. A pressure relief valve permits adjustment so that the desired amount of vaporization may be had. While pressure release may occur after passing the oil through a preliminary high pressure settling drum, it is preferred to adjust the pressure to 20 permit complete vaporization of the oil into one or more settling drums by means of said pressure relief valves. In these settling drums, the pressure is so adjusted as to permit complete vaporization of oil and deposition of dry lead salts, 25 which lead salts can be reclaimed and converted to plumbite. The pressure may be selected to allow the removal of lead salts as a suspension in unvaporized oil. The oil may be a portion of the original charge, or have been added for this 30 specific purpose as a carrier liquid. From the settling drums, the oil vapor is led to a fractionating tower, from which tower the oil vapors are led to a condenser and thence to a collecting tank which contains the finished product. The 35 bottoms from the fractionating tower contain high boiling sulphur compounds contained in oil and approximate 5% of the charge led to the fractionator. The fractionating tower may be dispensed with, although it is highly desirable as its use removes sulphur compounds advantageously.
- In the operation of the pipe still, the coil is maintained under sufficient back pressure to prevent vaporization in the tubes and under sufficient high velocity to prevent lead sulphide deposit on the interior of the tubes. The charge is heated high enough to completely vaporize the liquid as soon as the pressure is released. Upon the release of the pressure, the vapors are con- 50

ducted to a settling tower or drum where lead sulphide deposits as just explained.

Where the shell still is used for rerunning the oil which has been separated from the plumbite treating reagent by the aging operation, deposition of lead sulphide on the bottom of the shell still is controlled by circulating the still charge through spray nozzles which force the liquid over the bottom of the shell. In this case, the liquid will be distilled without steam up to a still temperature of 400° F., care being taken to avoid direct heating of that portion of the shell not covered by liquid. About 10% bottoms should be left in the still. If higher still temperatures are required, steam may be used. This usually results in considerable desulphurizing but the oil may be slightly sour. The sweet fractions can be segregated from the sour fractions which can be treated with calcium or sodium hypochlorite of suitable concentration, or with sodium plumbite or sulphur.

Where a pipe still is used, it is essential that the distillation at heating be carried out in the absence of steam inasmuch as the lead mercaptide will break down into mercaptans and lead hydroxide in the presence of water at relatively high temperature.

After the mercaptans have been removed, it is possible if desired, to further reduce the sulphur content by a judicious application of calcium hypochlorite. If this is done carefully, the resulting gasoline or naphtha will be sweet to doctor, have a pleasant odor and will be non-corrosive even when the distillation flask corrosion test is used. However, the oil after distillation is doctor sweet and non-corrosive, and the hypochlorite treatment should be used only in the case of extremely high sulphur gasolines where the sulphur content after the heat treatment is still above specified limits.

It will be observed from the above description that one feature of the invention is the aging of plumbite treated oil. Another feature of the invention resides in the use of heat treatment to decompose lead mercaptide. Where the sulphur content of the original gasoline permits, the lead sulphide may be removed by heating the oil to approximately 350° to 400° F. and filtering at this temperature. Apparently, lead mercaptide all breaks down at a temperature of the order of 300° to 350° F. After the heat treatment at about 350° F. under sufficient pressure to keep the oil in the liquid phase, it may be passed through a cooler, then to a filter press to separate the lead salts from the finished oil. In the alternative, the hot oil can be passed directly through a percolation filter to remove the lead salts from the finished oil.

A heat treatment to break down the lead mercaptide after the aging step may be omitted; in such a case, the oil is taken directly from the settling drums and passed through a percolation filter which is charged with moisture free fuller's earth and/or bone black or silica-gel. The spent filter medium containing the lead salts can be reclaimed by boiling with caustic solution in the presence of air. The solution containing the lead can be concentrated and removed, while the filter mass may be washed, dried and reused.

For a further understanding of the invention, reference is to be had to the following description and the accompanying drawings, wherein:

Fig. 1 is a diagrammatic view of apparatus,

conventionally illustrated, which may be employed for carrying out the present invention;

Fig. 2 is a similar view of a modified form of heater which may be used in the process.

Referring more particularly to the drawing, 5 raw untreated oil of suitable boiling range, with or without carrier liquid, may be contained in a tank 1. Usually this oil comprises raw gasoline or naphtha of high sulphur content, such as that obtained from certain of the Montana or Wyoming fields. In order to remove the undesirable sulphur compounds from such oil, or to reduce the same to a point where the remaining sulphur is not objectionable, the oil is transferred from the tank 1 by way of a pipe line 2 to the 10 suction side of a pump 3. Also entering the suction side of the pump 3 is a pipe line 4 by which spent caustic is introduced into the oil stream. An intimate mixture of the oil and spent caustic takes place in, for instance, an orifice mixer 5 so that the oil is effectively scrubbed and allowed to react with the spent caustic. From the orifice mixer, the mixture of oil and spent caustic is introduced into a separator 6 whereon there is separated from the oil a sludge 15 containing hydrogen sulphide, free sulphur and mercaptans, the sludge being removed by way of a valved draw-off line 7. From the separator 6, the oil is delivered to a pump 8 and is therein mixed with fresh caustic supplied through the 20 line 9 and scrubbed or mixed in the orifice mixer 10. After the fresh caustic has been allowed to react with the oil for a desired period of time, the mixture is passed into a second separator 11, where the sludge is removed by way of the 25 line 12 and treated oil passed to the suction side of a pump 13. A line 14 is employed to introduce the sodium plumbite solution into the oil withdrawn from the separator 11, and a mixture of sodium plumbite and oil is delivered to 30 and passed through an orifice mixer 15, to effect a thorough commingling of the sodium plumbite solution with the oil undergoing treatment. From the mixer 15, the oils are transferred by 35 way of a pipe line 16 to aging tanks 17 in which the oil is retained for a somewhat extended period of time and under a temperature of about 60° F. to secure an aging or reaction period. The spent plumbite solution together with any solid impurities which settle out are withdrawn 40 from the tanks 17 through valved draw-off line 18. Heating or cooling coils 19 may be used in the tank 17 for maintaining a temperature of the order of 60° F. of the oils therein contained.

After being retained in the tanks 17 for the desired period of time, the oils are forced by means of a pump 19 through a tubular heating coil 20 disposed in a heater 21, wherein the oils are heated to temperatures above 250° F. while maintained under super-atmospheric pressures sufficiently high to maintain such oils preferably in the liquid phase. A pressure relief valve 22 is provided in the outlet line 23 which leads from the coil 20 so that the pressures may be reduced to a desired point. The products are led from the coil 20 to a plurality of settling drums 24 in which the oils vaporize and are discharged through the overhead lines 25 to a fractionating tower 26. In the tanks 24, the lead salts are precipitated and withdrawn through the draw-off lines 27. Any high boiling sulphur compounds contained in the oils delivered to the fractionating tower 26 condense as a reflux in said tower which may be removed by way of the bottom draw-off line 28. The treated oil vapors leaving the top 75

of the tower 26 are cooled and liquefied in the condenser 29 and delivered to a storage container 30 as the treated finished product.

If a shell still is employed, as shown in Fig. 2, in lieu of the tubular type of heater indicated at 20, the drum 31 of the shell still is provided with a plurality of spray coils 32 within the same through which the liquid oils passing from the pump 19a are delivered under high velocity which 10 force the liquid over the bottom of the shell, thus avoiding excessive deposition of lead sulphide on the bottom of the shell. The draw-off line of the shell 31 is indicated at 33 and the pressure reducing valve at 22a.

15 It will be appreciated that the apparatus described is subject to modification and variations without departing from the scope of the present invention as the latter has been defined in the following claims.

20 What is claimed is:

1. The process of desulphurizing petroleum oil which comprises treating said oil with an alkaline plumbite solution without addition of sulphur, separating the plumbite solution from the oil and aging the oil for a period of several days in order 25 to remove traces of moisture and plumbite solution and to cause precipitation of lead-sulphur compounds.

2. The process according to claim 1 in which the oil is aged at a temperature above 60° F.

3. The process according to claim 1 in which the oil is aged at a temperature between 70° and 80° F.

35 4. The process of desulphurizing petroleum oil which comprises treating said oil with an alkaline plumbite solution without addition of sulphur, separating the plumbite solution from the oil and aging the oil for a period of several days in order

to remove traces of moisture and plumbite solution and to cause precipitation of lead-sulphur compounds, heating the oil to temperatures sufficiently high to decompose sulphur compounds remaining in the oil and separating resulting impurities from the oil. 5

5. Method in accordance with claim 4 in which the oil is heated above 250° F.

6. Method in accordance with claim 4 in which the oil is maintained under superatmospheric 10 pressure during the heating step.

7. Method in accordance with claim 4 in which the oil is heated above 250° F. while being maintained under superatmospheric pressure.

8. Method in accordance with claim 4 in which 15 the oil is separated from the high boiling sulphur compounds by fractional distillation following the heating step.

9. Method in accordance with claim 4 in which the oil is heated to a temperature between 300° 20 and 400° F.

10. Method in accordance with claim 4 in which the oil is heated under superatmospheric 25 pressure to a temperature between 300° and 400° F. and then filtered through solid adsorbent material.

11. The method of desulphurizing petroleum oil without addition of free sulphur which comprises subjecting the oil to treatment with an alkaline plumbite solution, aging the treated oil 30 for a period of several days in order to cause precipitation of lead-sulphur compounds, and filtering the aged oil through a solid adsorbent material.

12. Method according to claim 1 in which the oil is subjected to treatment with a hypochlorite 35 following the aging step.

CHARLES M. RIDGWAY.
